UNITED STATES PATENT OFFICE.

ERNEST O. HOWLE, OF NASHVILLE, TENNESSEE, AND JOSEPH E. LEONARD, OF CEDAR RAPIDS, IOWA.

STOVE AND RANGE.

1,393,129.

Specification of Letters Patent. Patented Oct. 11, 1921.

Application filed July 3, 1920. Serial No. 393,920.

To all whom it may concern:

Be it known that we, ERNEST O. HOWLE, a citizen of the United States, residing at Nashville, in the county of Davidson, State 5 of Tennessee, and JOSEPH E. LEONARD, a citizen of the United States, residing at Cedar Rapids, in the county of Linn and State of Iowa, have invented certain new and useful Improvements in Stoves and 10 Ranges, of which the following is a specification:

This invention relates to stoves and ranges, more particularly those of the elevated oven type, and the object of the invention is to 15 provide for the use at will, and without changing adjustments or shifting apparatus, of either solid or gaseous fuel for combustion, and for the heating, more especially, of the oven.

20 The invention is fully disclosed in the description and claims following, reference being had to the accompanying drawings, in which:—

Figure 1 is a central section from front 25 to back, in a vertical plane of the bottom parts of an oven containing our improvements. Fig. 2 is a similar section, but in a plane transverse to that indicated in Fig. 1. Fig. 3 is a plan view of the parts below 30 the line 3—3 of Fig. 2 with the baffle-plate removed. Fig. 4 is a plan view of the front side of the baffle-plate. Fig. 5 is a fragmentary front elevation of a range including this invention, showing the oven, top 35 portion of the range proper, and connecting flue.

In the drawing, the numeral 5 denotes the outer shell or casing, and 6 the inner chamber of an oven. The outer chamber communicates by a flue (not shown) which at 40 its upper end connects with the collar 7, and at the lower end is supposed to connect with a similar collar on the stove, not shown. The products of combustion from the stove 45 or range, which is adapted to burn solid fuel, pass through the flue and the spaces between the outer and inner chambers of the oven, and thence up the chimney through a similar collar, not shown, at the top of the oven 50 as indicated by the black-faced arrows. The oven in this respect is of familiar construction, and need not be specifically described.

Where gas may be conveniently led to the stove it is found to be very desirable to arrange the stove for the use of both fuels,

solid fuel for the more continuous and heavy service, as in winter, and gas for the lighter and more intermittent service. Our improvement embodies such a construction as applied to an oven, and the same will now be 60 described.

Referring to Fig. 2, it will be seen that the bottom of the inner chamber is convexed from side to side, the inclined wings 8 being preferably joined to a central, trough-like 65 casting 9, which crosses the flue above mentioned, and serves to deflect the products of combustion to each side of the oven as indicated. A little above this bottom is mounted a baffle-plate 10, which forms the working 70 bottom of the oven. This is preferably made of sheet-iron, but is reinforced by a casting 11, centrally concaved at 12, and with upwardly inclined sides fastened to the main sheet. The baffle-plate is considerably nar- 75 rower than the inner chamber of the oven, and is supported principally at the front by an upward extension 14 of the oven bottom, and at the back and corners by inwardly extending lugs or flanges 15. This leaves 80 openings at 16 for the products of gaseous combustion to pass through and directly into the oven. The baffle-plate is also prefer- 85 ably perforated at 17 for convenience in lighting the gas. Outlets at 18 at the rear, and near the bottom of the oven permit the outflow of the hot air, after it has flowed to the top of the oven, and thence down the back side thereof.

Directly under the hollow of the baffle- 90 plate is mounted a tubular gas-burner 19, its front end resting on the inclined extension 14, and its rear end on a prop 20. The burner is preferably made elliptical in cross section, and is pierced at the sides with a 95 multitude of small holes 21 to serve as gas-jets. Near the rear end an elbow 22 depends through a hole 23 in the casting 9, the hole being enlarged adjacent to the elbow, so as to supply air for combustion to the 100 burner. A similar hole 24 is provided near the other end of the burner. The elbow of the burner connects with a service-pipe 25.

The course of the air is indicated by feathered arrows, and that of the products 105 of gaseous combustion, by thin, unfeathered arrows.

The construction admits of the use of either fuel at will, and without the shifting of a damper, or any other part of the stove 11

or oven in changing from one kind of fuel to the other. The openings in the oven for the circulation of the gaseous heat do not in the least prevent or retard the proper heating of the oven, while the location of the burner, inside the oven, but screened from its contents by the baffle-plate, tends to give it very rapid action in heating, and the highest efficiency in the maintenance of the temperature.

It is to be noted that the air inlets which support the combustion of gas have no communication with the passages for the products of solid fuel combustion, consequently there is no leakage of smoke, nor any tendency on their part to retard the regular draft of the stove.

Having thus described our invention, we claim:

20 1. In a range having an elevated oven connecting with the range combustion chamber by a vertical flue, an oven having an outer chamber communicating at the bottom with said flue, and an inner chamber spaced 25 away therefrom at the bottom and sides, a double bottom for the inner chamber, the lower one inclining upwardly from a deeper central depression crossing said flue from front to back of the oven, a long gas-burner 30 set relatively central to said depression, and a superimposed baffle-plate adapted to spread the gas flame toward the sides of the oven parallel with the burner, the upper bottom having openings for the products of gaseous 35 combustion.

2. In a range having an elevated oven connecting substantially centrally with the range combustion-chamber by a vertical flue, and having an outer chamber and an inner 40 chamber spaced away therefrom at the bottom and sides, a double bottom for said inner chamber, comprising a flat working bottom, pierced to admit gaseous products of combustion, a baffle-plate thereunder ex-

tending from front to back and inclined upwardly toward its other sides, a long, tubular gas-burner mounted centrally thereunder, and a lower bottom below said burner, having upwardly inclined sides springing from a deeper middle depression extending across 50 said flue, and provided with air inlets closed to the products of combustion from the range below.

3. In a range having an elevated oven composed of outer and inner chambers 55 spaced apart at bottom and sides for the passage of products of combustion from the range, a flue extending vertically from the range to the oven bottom, a double bottom for the inner chamber of the oven, the lower 60 one having a middle depression extending from front to back of the oven, with upwardly inclined wings springing therefrom, air inlets therefor closed to said products of combustion, a gas-burner extending lengthwise of said depression, with a connecting elbow through one of said inlets, a superimposed inner bottom for the oven with inlets for gaseous products of combustion, and outlets therefor isolated from any other 70 products of combustion.

4. An oven for ranges, comprising an outer and an inner chamber, spaced apart for the passage of products of combustion the inner chamber having a double bottom, 75 of which the lower has a middle trough or depression, with sides upwardly inclining therefrom, a tubular gas-burner mounted lengthwise of the trough, and a flame-spreading baffle-plate over the burner and below 80 the upper bottom.

In testimony whereof we affix our signatures in presence of two witnesses.

ERNEST O. HOWLE.
JOSEPH E. LEONARD.
